Primary Examiner — Kevin Rudzinski(74) *Attorney, Agent, or Firm* — Sterne, Kessler, Goldstein & Fox PLLC**CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a second embodiment thereof. The broken lines around the Figures showing a display screen or portion thereof form no part of the claimed design.
